CLAIM

We claim the ornamental design for a basket in bowl, as shown and described.

DESCRIPTION

FIG. 1 is an isometric view of a basket in bowl;
FIG. 2 is another isometric view of the basket in bowl of FIG. 1;
FIG. 3 is a top plan view of the basket in bowl of FIG. 1;
FIG. 4 is a bottom view of the basket in bowl of FIG. 1;
FIG. 5 is a front elevation view of the basket in bowl of FIG. 1;
FIG. 6 is a rear elevation view of the basket in bowl of FIG. 1;
FIG. 7 is a left side elevation view of the basket in bowl of FIG. 1; and,
FIG. 8 is a right side elevation view of the basket in bowl of FIG. 1.

The broken lines in the figures represent portions of the basket in bowl that form no part of the claimed design. The dash-dot-dash boundary lines in the figures define the bounds of the claimed design.
